UNITED STATES PATENT OFFICE.

ANDREW G. GREIG, OF NEW YORK, N. Y., ASSIGNOR TO THE BIGELOW
CARPET COMPANY, OF MASSACHUSETTS.

DESIGN FOR CARPETING.

SPECIFICATION forming part of Design No. 30,452, dated March 28, 1899.

Application filed December 29, 1898. Serial No. 700,664. Term of patent 3½ years.

To all whom it may concern:

Be it known that I, ANDREW G. GREIG, a citizen of the United States, and a resident of the city, county, and State of New York, 5 have invented a new and original Design for Carpeting, of which the following is a specification.

My design, as shown in the drawing A, consists in a new design for carpeting.

10 The design is characterized by bold medallion-like figures, each made up of a central rosette from which radiate conventional leaf-like forms and surrounded by a wreath of conventional flowers and foliage. The central rosette of the medallion-like figures is 15 frequently repeated elsewhere in the design,

some of these rosettes being inclosed by an outline reproduction of the radiating forms of the medallion. The whole is arranged upon a suitable background.

What I claim as new, and desire to secure by Letters Patent, is—

The design for carpeting substantially as shown and described.

In testimony whereof I have signed my 25 name to this specification in the presence of two subscribing witnesses.

ANDREW G. GREIG.
